UNITED STATES PATENT OFFICE.

STEPHEN BATTNER, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

PIANO FALL BOARD.

Application filed October 26, 1925. Serial No. 64,771.

This invention relates to the means for equalizing the backward and forward movements of the fall-board of a piano at both ends by taking hold of it at either end.

- 5 In the constructions hitherto employed, the fall board descended more or less on its backward stroke, leaving a large and unsightly gap between its upper edge and the adjacent top frame or panel of the piano.
- 10 One object of the present invention is to so construct the equalizing means and guide the fall board in such a manner, that its horizontal rear part is caused to travel in a straight horizontal path and remain level
- 15 in all positions, avoiding the above objection.

A further object is the production of a simple and inexpensive mechanism which has the additional merit of compactness and 20 which is especially applicable to player pianos.

In the accompanying drawings:

Figure 1 is a top plan view, partly in section, of a piano embodying the improvement, showing the rear member of the fall-board retracted and the front member folded. Figure 2 is a similar view showing said rear member projected and the front member unfolded. Figure 3 is a bottom plan view of said rear member, with the parts in the position shown in Fig. 1. Figures 4 and 5 are cross sections on lines 4-4 and 5-5, Fig. 1, respectively.

Similar characters of reference indicate 35 corresponding parts throughout the several views.

10 indicates the key-bed; 11 the keys; 12 the usual fixed bar or so-called bevel strip arranged above the keys; 13 the top frame 40 of the piano; 14 the rear member of the fall-board; and 15 the front member hinged to the rear member. This rear part or member is slidable horizontally upon fixed rails or guides 16 mounted upon the usual key-blocks 17 arranged on the inner sides of the cheeks 18. The rear part of the fall-board carries on its rear portion the customary upright wall or back strip 19, while the hinged front part has the usual front strip 20. These strips, in the folded position of the fall-board shown in Fig. 4, rise nearly to the lower edge of the top frame, leaving just enough clearance to permit the fall board to be freely shifted back and forth.

The backward movement of this rear member is limited by stop pins 21 extending inwardly from the cheeks or piano case, while its forward stroke is limited by stops 22, preferably in the form of vertical screws projecting from the underside of the rear fall-board member and arranged to enter forked centering-lugs or guides 23 secured to the upper side of the bevel strip 12.

The means for equalizing the sliding movement of the fall-board at both ends, 65 comprise a pair of horizontally-swinging levers 24, each fulcrumed between its ends upon a block or bracket 25 projecting rearwardly from the bevel strip. The inner arms of these levers are pivoted together by 70 a pin 26 to transmit the movement of one to the other, while their outer ends, which are preferably forked, embrace pins or screws 27 projecting from the underside of the rear member 14. The pivot pin 26 is secured to 75 one of the levers and passes through a longitudinal slot 28 in the other.

By this construction and arrangement of parts, the rear part of the fall board with the hinged member 15 carried by it, is bodily 80 slid backward or forward equally throughout its length by seizing either end of the board, the connected equalizing levers producing this uniform movement without restraint and very little friction.

As the fall board slides horizontally in a straight rectilinear path, the comparatively small space between its upright back strip 19 and the vertical front strip 20, when the board is folded, is maintained in the rear as 90 well as the front position of the board, presenting a slightly appearance of these parts in all positions thereof.

This sliding movement of the fall board combined with the equalizing mechanism 95 herein shown, also provides a compact structure, which affords the advantage of enabling the depth of the piano case to be made about an inch less than do the devices heretofore in use, especially in player pianos. 100

I claim as my invention:

1. In a piano, the combination of a keyboard, guides at opposite ends of the keyboard and a longitudinal strip fixed above it, of a fall-board slidable on said guides, 105 a pair of horizontally-swinging equalizing levers extending lengthwise of the fall-board and fulcrumed on said strip, said le-

vers being pivoted together at their inner ends and having their outer ends pivotally connected to opposite ends of the fall-board.

2. In a piano, the combination of the keyboard, guides at opposite ends of the keyboard and a longitudinal strip fixed above it, of a fall-board slidable on said guides, a pair of horizontally-swinging equalizing levers extending lengthwise of the fall-board

and each fulcrumed between its ends on said strip, said levers being pivoted together at their inner ends and having their outer ends pivoted to opposite ends of the fall-board, and forked centering lugs mounted on said strip, the fall-board carrying stops arranged to enter said lugs. ¹⁰ ¹⁵

STEPHEN BATTNER.
